H. V. PAYNE

SAFETY PILOT AND CUT-OFF DEVICE FOR GAS BURNERS

Filed July 8, 1924

Fig. 1

UNITED STATES PATENT OFFICE.

HARRY V. PAYNE, OF LOS ANGELES, CALIFORNIA, ASSIGNOR TO PAYNE FURNACE AND SUPPLY COMPANY, OF LOS ANGELES, CALIFORNIA, A CORPORATION OF CALIFORNIA.

SAFETY PILOT AND CUT-OFF DEVICE FOR GAS BURNERS.

Application filed July 8, 1924. Serial No. 724,771.

To all whom it may concern:

Be it known that I, HARRY V. PAYNE, a citizen of the United States, residing at Los Angeles, county of Los Angeles, and State of California, have invented a new and useful Safety Pilot and Cut-Off Device for Gas Burners, of which the following is a specification.

This invention relates to gas burners suitable for use in gas furnaces, water heaters, etc., in which a main burner is provided for heating purposes and is adapted to be turned on and off by means of a valve operated manually or by thermostatic or other automatic control, and in which a small residual or pilot flame is continually maintained for the purpose of relighting the gas at the main burner when such gas supply is turned on.

20 The principal object of this invention is to provide means for cutting off the supply of gas both to the pilot and to the main burner in case of extinguishment of the pilot flame, thereby preventing waste of gas and eliminating the danger of explosions resulting from the accumulation of unburned gas.

Another object of the invention is to prevent the gas supply to the main burner from being subsequently turned on by the operation of the manual valve or of the thermostatic or other control means, until the safety control device has been reset, so that danger of explosion on attempting to relight the main burner is avoided and a person will be advised that the pilot is out and may relight the same and reset the control device.

Another object of the invention is to provide electrical means for operation of the safety cut-off valve, said electrical means being controlled by thermally controlled operating means in response to the cooling off of the pilot burner upon extinguishment thereof.

Another object of the invention is to provide for breaking the electrical control circuit upon operation of the cut-off valve so as to prevent waste of electricity and overheating of the electrical device.

A further object of the invention is to provide a simple means for resetting the safety control device when the pilot flame is relighted, and to so arrange the thermally

controlled operating means and the electrical contact means controlled thereby that such contact means will be operated so as to cause closure of the cut-off device upon the cooling off of the pilot burner but will not be affected upon the heating thereof subsequent to relighting. This enables one to relight the pilot and reset the control device before the pilot burner has heated up, with the result that the main burner will operate in a normal manner and the thermal means operated by the heat of the pilot burner will be returned to normal operating position and the device will therefore be in readiness to again act as before in case the pilot light is extinguished. This latter feature adds materially to the convenience and utility of the device and is an important advantage thereof.

The accompanying drawings illustrate embodiments of my invention and referring thereto.

Fig. 1 is a side elevation of a gas burner provided with my improved safety pilot and cut-off device.

Fig. 2 is a section on line 2—2 in Fig. 1.

Fig. 3 is a section on line 3—3 in Fig. 2.

Fig. 4 is an inverted horizontal section on line 4—4 in Fig. 1.

Fig. 5 is an end elevation of the electromagnetic control means and the valve operating means controlled thereby.

Fig. 6 is an inverted horizontal section on line 6—6 in Fig. 1 showing the cut-off valve.

Fig. 7 is a vertical section on line 7—7 in Fig. 6, showing the cut-off valve in closed position.

Fig. 8 is a detailed view of a modified form of the electrical contact means operated by the thermally controlled means.

Referring to Fig. 1 the main burner 1, which may be provided with the usual air mixing device 5, is connected by pipe 2 to the gas supply pipe 3, and a valve 4 is provided for turning on and off the supply of gas to the burner 1. Such valve 4 may as shown, be adapted for manual operation, and in such case it may be located adjacent the burner or at any desired distance therefrom or it may be provided with means for remote control, for example electrically or otherwise. In case the burner is to be used in connection with water heaters where a

certain temperature is to be maintained, valve 4 may be replaced by a thermostatically controlled valve of any of the well-known types of such valves so as to be turned on and off in correspondence with the decrease and increase in the temperature of the water. Valve 4 may also be adapted to be turned on and off in correspondence with the flow of water through the water heater, 5 when used in connection with water heaters which operate on this principle. My invention however is not concerned with the construction and operation of this valve 4 for the main burner and I have therefore shown 10 in the drawings only a manual valve at this point. It is to be understood however that my safety pilot and cut-off valve may be used in connection with a gas burner provided with a valve adapted for operation in 15 any of the above described manners or in any other way.

My invention comprises a pilot burner 6 located adjacent the main burner 1 and preferably provided with a burner tip 7 of 20 soap stone or other suitable material adapted to assist in maintaining a small flame of the desired form. Said pilot is connected by a pipe 46 to the gas supply pipe 3, at a point preceding the main control valve 4, 25 so that the operation of said pilot burner is independent of said valve. A thermally controlled element 8, comprising for example two metal strips 9 and 10 of unequal thermal expansions, is mounted on the side of the 30 pilot burner and adapted to receive heat therefrom, by conduction through the walls of the burner and through such thermal element, or otherwise. The construction and arrangement of the thermally controlled element is such that when the pilot flame is 35 extinguished and the pilot burner is consequently cool such element occupies substantially the position shown in Fig. 1, and upon heating of such pilot burner by the pilot 40 flame the thermally controlled element is bent and moves to the right, occupying substantially the position indicated in dotted lines at 8' in said figure. Suitable circuit closing means are arranged for operation by 45 the thermally controlled element, said means comprising for example, a pair of electrical contact members 11 and 12, mounted on an insulating supporting block 60 which may be secured to pipe 46 by means of a set screw 50 64. Said contact members are normally out of contact with each other so as to interpose a break in the electrical circuit at this point, and are adapted to be operated, so as to make contact, only upon the reverse 55 movement of the thermally controlled means during cooling of the pilot burner resulting upon extinguishment thereof. Referring especially to Figures 2 and 3, the means provided for this purpose may comprise an 60 operating projection or lug 13 on contact 11,

said contact being preferably made of spring metal, and a projection or arm 14 on the lower end of the thermally controlled element. Arm 14 may be provided with side pieces 15 upon which is pivoted a swinging 70 member or finger 16. In the movement of the thermally controlled element to the right during heating of the pilot burner, such finger 16, upon engagement with lug 13, swings on its pivot 19 and passes over such lug 75 without operation of contact 11 and therefore without closing the normally open break in the circuit between contact members 11 and 12. In the reverse movement of the thermally controlled element resulting from 80 cooling due to extinguishment of the pilot flame, however, finger 16 again engages lug 13 and is in this case prevented from swinging on its pivot by engagement of its upper end 17 with the lower end 18 of member 14, 85 so that the contact 11 is pressed down as indicated in dotted lines in Fig. 3 to make connection with contact 12 and thus close the circuit at this point.

The cut-off valve proper is located in the 90 main gas supply pipe 3 and may be of any suitable construction, comprising, for example a casing 20 provided with a lateral extension 21 in which is journaled a shaft 22. An arm 23 is mounted upon said shaft 95 and adapted to be moved therewith, for example, by engagement of a square opening 24 with a square portion 25 on said shaft. Said arm 23 carries a pair of valve members 26 adapted, upon movement of the valve to closed position, as indicated in dotted lines in Figure 6, to engage the tapered valve seats 27 and thereby completely cut off the 100 passage of gas through the opening 28 in casing 20. During normal operation of the burner the cut off valve is held in the position indicated in full lines in Fig. 6 as hereinafter described. On the lower end of shaft 22 is mounted an arm or lever 30, said arm being normally held in the position indicated 105 in Fig. 4 by suitable retaining means, for example by engagement with a catch or pin 31 on a tripping member 32. When said arm is in this position the cut off valve is in normal or open position. The outer end of arm or lever 30 may extend beyond the catch 31 and may be formed as a handle 30'. Electrically operated means are provided for moving member 32 so as to cause the catch 110 31 to release arm 30 and permit the latter to be moved by spring 33, which is coiled around shaft 22, so as to swing the cut off valve to closed position. The electrically operated means for this purpose may comprise an electromagnet 34 mounted on a supporting plate 35, said supporting plate being for example mounted in turn on the casing 20 of the cut off valve. The tripping member 32 may also be hinged as at 36 on supporting plate 35, the electromagnet 34 being 115 120 125 130

mounted directly above said member 32 which constitutes an armature of the electromagnet so that upon energization thereof said member 32 is raised, thereby permitting closure of the cut off valve as above described. The electrical control circuit for operation of the electromagnetic means may comprise a wire 37 leading from a suitable source of current (for example a battery, as indicated diagrammatically at 39) to contact 11, a wire 38 leading from contact 12 to one end of the winding of the electromagnet 34 and a return connection from the other end of said winding to the source of current. Said return connection is preferably provided with contact means adapted to break the circuit upon closing movement of the cut off valve. For this purpose the return wire 40 leading to the source of current may be connected to a contact member 41 adapted to make contact, when the device is in normal position, with a contact member 42 on arm 30, from which a wire 43 leads to electromagnet 34. Said contact members 41 and 42 are so located that the connection between them is broken upon movement of arm 30 to close the cut off valve. Binding posts 48 and 49 may be connected to the respective ends of the electromagnet winding and may be adapted for connection thereto of wires 38 and 43, and a binding post 50 may be connected to contact member 41 and adapted to receive wire 40, all of said binding posts being mounted for example on an insulating support 51 secured to the supporting plate 35. The wires comprising the electrical circuit are preferably insulated and may if desired be encased in suitable insulating coverings 53.

A manual valve 45 may be provided in pipe 46 for regulating the supply of gas to the pilot burner 6, and a manual valve 47 may also be provided in the main gas supply pipe 3 for regulating the supply of gas to both the main burner and the pilot burner or for entirely shutting off all supply of gas in case the burner is to be unoperated for a long period of time.

Other means may be provided such as shown in Fig. 8 for causing operation of the electrical circuit closing means by the movement of the thermally controlled element 8. In this case the lower end of such element may be pointed or formed in such a way as to form a suitable tip 55 adapted to engage an operating spring 56 secured to a contact arm 11 provided with a contact point 11'. Said contact arm and spring may be mounted on a block 57 pivoted at 58 on brackets 59 mounted on the insulating supporting block 60. Suitable spring means such as leaf spring 61 may be provided so as to engage block 57 and hold the contact member 11 normally in open position. A stop 62 is provided for limiting the movement of block

57 and the contact member carried thereby under the action of said spring. In the movement of the thermally controlled element to the right during heating of the pilot burner the tip 55 of such element engages 70 the operating spring 56 but stop 62 prevents movement of the block 57 and spring 56 therefore yields sufficiently to permit the tip 55 to pass thereover to its normal position during the operation of the burner. In case 75 of extinguishment of the burner flame the reverse movement of the thermally controlled element 8 will again cause the tip 55 to engage spring 56 and said spring is sufficiently strong to cause the contact arm 11 to 80 be pressed down against the resistance of spring 61 so as to cause the contact point 11' to make connection with contact member 12, thus establishing the electrical circuit.

The operation of my improved safety 85 pilot and cut off device is as follows:

Upon first starting the burner the arm or lever 30 is "set" or moved so as to open the cut-off valve and close connection between contact members 41 and 42, the weight of tripping member 32 causing said member to rest on said arm or lever so that when the lever has passed beyond the pin or catch 31, said catch will drop and engage the edge 90 of lever 30 to hold it in this position (see Fig. 5). Manual cut-off valve 47 is then opened if not already in that condition and the main burner and pilot are lighted, valve 45 being adjusted to give the proper size pilot flame and valve 4 being opened 100 manually or by any of the above mentioned means which may be provided for that purpose. At the beginning of such operation the thermally controlled element occupies the position shown in full lines in Fig. 1, but the heat of the pilot flame is conducted through the walls of the pilot burner 6 or otherwise to said element and causes the same to bend and finally to move to the position indicated at 8'. By either of the operating means above described for the circuit closer the thermally controlled element is permitted to move to this position without causing operation of the contact member 11 to close the break in the circuit at this point. 115 This is important for if such contact member were operated at this time the cut-off valve would be operated and both the main burner and pilot immediately extinguished, and in that case it would be necessary for one to manually hold the lever 30 so as to maintain the cut off valve in open position until the heat of the pilot flame had caused the thermally controlled element to move to normal position or at least to pass the operating member on contact member 11. 120

When the thermally controlled element 8 has thus been moved to normal position it will remain substantially in this position 125 so long as the pilot flame is maintained, re-

gardless of whether the main burner 1 is turned on or off, for as stated said element receives its heat principally by conduction or otherwise from the pilot burner 6 and is 5 only slightly affected by radiated heat from the main burner. Any tendency of such radiated heat from the main burner to affect the thermally controlled element is counteracted to a large extent by the effect of the cold air 10 passing upward to the burner to support combustion of the gas. Valve 4 may therefore be operated at will or by suitable automatic or thermostatic control means so as to regulate the heating effected by burner 1 15 without causing any operation of the safety cut-off device.

In case, however, while the main burner 1 is shut off, the pilot flame should be accidentally extinguished, for example, by a sudden 20 gust of wind or by a cutting off of the gas supply at some point in the gas main, the pilot burner and the thermally controlled element will immediately begin to cool off and such element will return to its original 25 position, the direction of this movement being to the left in Figs. 1 and 3. Such movement of the thermally controlled element will operate the circuit closer so as to make connection between contacts 11 and 12 30 as above described, which in turn will cause the lever 30 to be released, due to attraction of tripping member 32 by electromagnet 34, thus permitting spring 33 to move said lever so as to close the safety cut-off valve and to 35 break the electrical connection between the circuit opening means comprising contact members 41 and 42. The gas supply will therefore be entirely cut off from both the main burner and the pilot burner so that a 40 subsequent opening of valve 4 will have no effect. This not only prevents the escape of gas through the pilot burner 6 upon extinguishment thereof, but also prevents the much larger and more dangerous loss of gas 45 which would result in the absence of such a cut-off device upon the reopening of valve 4 while the pilot flame was not burning. The breaking of the electrical connection also 50 prevents waste of electricity and consequent weakening of the battery 39, and also prevents overheating of electromagnet 34 which might result from continued passage of current therethrough. Upon discovery that the pilot flame is extinguished for example by 55 observing a failure of the main burner to re-light upon opening of valve 4 it is only necessary for one to again set lever 30 and re-light the burner as above described, the tripping device automatically returning to normal 60 position. The resetting of lever 30 not only restores the supply of gas to both the main burner and the pilot burner but again places the electrical control circuit in normal condition, the connections being closed at 65 the circuit opening switch comprising con-

tacts 41 and 42 and open at the circuit closing switch comprising contacts 11 and 12. In this connection it should be noted that in the operation of the thermally controlled means during cooling, contact member 11 is 70 first operated to close the break in the circuit at this point and said thermally controlled means then passes on and releases said contact member so as to again interpose a break in the electrical circuit. This is of 75 great advantage since the fact that the circuit is automatically broken in this manner following closure of the cut-off valve permits said cut-off valve to be reopened and the pilot burner relighted without the necessity 80 of any manual operation other than to open said valve.

What I claim is:

1. A safety cut-off device for gas burners comprising in combination with a gas 85 burner and means for supplying gas to said burner, thermally controlled means adapted to be heated by the flame at said burner and to be operated by the heat thus received, an electrical control circuit including a source 90 of current and also including circuit-closing means normally interposing a break in said circuit, said thermally controlled means being adapted, upon movement thereof during cooling due to extinguishment of 95 said flame, to first operate said circuit-closing means so as to close said break in the circuit and then release said circuit-closing means so as to reopen said break in the circuit, and said circuit-closing means being 100 adapted to be operated by said thermally controlled means so as to close said break in the circuit only during movement of said thermally controlled means upon cooling 105 thereof, electro-magnetic means also included in said control circuit, and valve means in said gas supply means and adapted to be operated under control of said electro-magnetic means so as to cut off the supply 110 of gas to the burner when said break in the circuit is closed.

2. A safety cut-off device for gas burners comprising, in combination with a main burner and a pilot burner and means for supplying gas to said burners, thermally 115 controlled means adapted to receive heat from a flame at the pilot burner and to be operated by the heat thus received, an electrical control circuit, contact means included in said circuit and normally defining a break therein, electro-magnetic means also included in said control circuit, and valve means included in said gas supply 120 means and operable under control of said electro-magnetic means to cut off the supply 125 of gas upon closure of said normally open break in the control circuit, said thermally controlled means being adapted during cooling thereof to engage said contact means and operate the same to close said break in 130

the circuit and being adapted during heating thereof to yieldingly engage said contact and pass out of such engagement while leaving said break in the circuit open.

- 5 3. A safety cut-off device for gas burners comprising, in combination with a main burner and a pilot burner and means for supplying gas to said burners, thermally controlled means adapted to receive heat 10 from a flame at the pilot burner and to be operated by the heat thus received, an electrical control circuit, contact means included in said circuit and normally defining a break therein, electro-magnetic means also included 15 in said control circuit, and valve means in-
- cluded in said gas supply means and operable under control of said electro-magnetic means to cut off the supply of gas upon closure of said normally open break in the control circuit, said thermally controlled 20 means being adapted to effect contact between said contact means and close the break in the control circuit only upon movement thereof during cooling and being adapted in such movement during cooling to first effect 25 such contact and then break the same.

In testimony whereof I have hereunto subscribed my name this 28th day of June 1924.

HARRY V. PAYNE.
